Attorney.

UNITED STATES PATENT OFFICE

EUGENE WHINNEN, OF LOS ANGELES, CALIFORNIA, ASSIGNOR TO SULLIVAN MACHINERY COMPANY, A CORPORATION OF MASSACHUSETTS

CORE DRILL

Application filed December 26, 1923. Serial No. 682,599.

My invention relates to core drills.

It has for its object to provide an improved core barrel and more particularly an improved core barrel especially adapted to use 5 in connection with oil wells wherein mud fluid is used, this core barrel being of improved construction and providing improved means for supplying such mud fluid to the bottom of the hole.

10 In the accompanying drawings I have shown for purposes of illustration one form which my invention may assume in practice.

15 In these drawings,—

Fig. 1 is a side elevation partially in section of one form of my improvement.

Fig. 2 is a sectional view on line 2—2 of Fig. 1.

20 Fig. 3 is a sectional view on line 3—3 of Fig. 1.

Fig. 4 is a sectional view on line 4—4 of Fig. 1.

25 In this illustrative construction I have shown a core barrel comprising a main barrel member 1 of one diameter and a lower bit carrying section generally designated 2 of the same diameter, both sections of the same being improved as hereinafter described.

30 In my improved construction the member 1 is provided at its upper end with a coupling 3 of the threaded type having a fluid inlet 4 extending partially therethrough, one end of the coupling being adapted to be connected to the rod line and the other being 35 threaded into the open upper end of the member 1. As shown, this member 3 is also provided with a plurality of lateral fluid passages 5, herein three, leading from the inlet 4 to the exterior of the coupling member, and these lateral fluid passages are connected through suitable pipe connections 6 welded 40 to the exterior of the member 1 as shown in Fig. 3 so that the fluid received through the passage 4 in the coupling may be transmitted 45 down along the outside of the barrel member 1. More particularly it will be noted that the inner threaded end of the coupling 3 is 50 in the form of a solid plug 7 so that the bore is plugged in such manner that all the liquid will pass through the pipes 6 while the core

may rise up to the plug within the member 1 as usual. Operatively connected to the bottom of the member 1 is also a member 8 having an externally threaded reduced sleeve 9 threaded to the inside of the lower end of the member 1. This member 8 is in turn provided with vertically disposed openings 10 therein which are formed in three radially disposed wings 11 thereon and adapted to receive the lower ends of the pipes 6. During assembly of the barrel after the members 1 and 8 are connected together the lower ends of the pipes 6 are inserted within the bores 10 and thereafter the pipes are connected to the head 3 and suitably welded in position. As shown, these openings 10 communicate with passages in a bit and core lifter carrying member 13 which is threaded on to a reduced externally threaded sleeve 14 on the lower end of the member 8. Herein, both the member 8 and the member 13 are of the same cross section, i. e. that shown in Fig. 2, and slanting passages 15 are provided in the wings 11 on the member 13 leading over to one edge of each wing so that the passage opens out into the bottom of the hole at one side of the diamonds (not shown) which are carried on the lower ends of the wings and on the lower end of the body of the member 13. As shown, a suitable core lifter 16, preferably of usual split or resilient form, is also carried within the member 13, preferably just below the threaded sleeve on the member 8.

As a result of my improved construction 85 it will be noted that a large core is obtained from a relatively small hole and that at the same time it is made possible to supply fluid to the wings from the core barrel and also to direct that fluid to the bit through the wings 90 thereof to the bottom of the hole without passing any fluid around the core to the hole, this being a feature especially desirable where the core is of a character not calculated to withstand the action of fluid. Moreover, it 95 will be noted that this result is obtained at the same time that it is made possible to retain the wing form of bit or bit and barrel for the effect of the same in slapping the mud fluid into the hole as well as to enable the 100

up-flow of mud fluid from the bottom of the hole.

While I have in this application specifically described one form which my invention may assume in practice, it will be understood that this form of the same is shown for purposes of illustration and that the invention may be modified and embodied in various other forms without departing from its spirit 10 or the scope of the appended claims.

What I claim as new and desire to secure by Letters Patent is:

1. A core barrel comprising a single core receiving barrel member, a bit thereon having 15 projecting wings and fluid conducting passages in its wings, said barrel member forming a connection between the drill rods and said bit, and means including a plurality of separate members disposed along the outside 20 of said barrel member for delivering fluid from the top of said barrel member through the passages in said wings on said bit to the bottom of the hole, each of said last mentioned members having a fluid conducting 25 passage therein communicating with one of the passages in the wings.
2. A core barrel comprising a single core receiving barrel member, means for closing the top thereof, a winged bit on said barrel 30 member having fluid conducting passages in its wings, said barrel member forming a connection between the drill rods and said bit, and means including a plurality of separate fluid conducting members extending length- 35 wise of said barrel member on the outside thereof for delivering fluid from above said closure means externally of said barrel member and through the passages in said wings on said bit to the bottom of the hole, each of 40 said fluid conducting members having a fluid conducting passage therein communicating with a passage in the wings.
3. A core barrel comprising a single core receiving barrel member, means for closing 45 the top thereof, a winged bit on said barrel member having a fluid conducting passage in each of its wings, said barrel member forming a connection between the drill rods and said bit, and means including a plurality of sep- 50 arate elements extending along the outside of said barrel member for delivering fluid from the rods through said closure means externally of said barrel member and through the passages in said wings on said bit to the bottom of the hole, each of said elements having a fluid conducting passage therein commun- 55 icating with one of the passages in the wings.
4. A core barrel comprising a core receiv- 60 ing barrel member having a core chamber therein, the upper end of said chamber being closed, a core cutting bit thereon, said barrel member and bit being of substantially winged cross section throughout their length and of substantially the same diameter, and means 65 for delivering fluid from the upper end of

the barrel and through the wings on said barrel member and said bit to the bottom of the hole.

5. A core barrel comprising a core receiving barrel member having a core chamber 70 therein, the upper end of said chamber being closed, a core cutting bit thereon, said barrel member and bit being of substantially winged cross section throughout their length and of substantially the same diameter, and means 75 for delivering fluid to the top of said barrel and externally of the interior thereof and through the wings on said barrel member and bit to the bottom of the hole.

6. A core barrel comprising a barrel member, a bit section, said bit section having wings thereon, and means for delivering fluid to the top of said barrel and externally of the interior thereof to and through said wings to the bottom of the hole, said means including a laterally ported plug at the top of the barrel and piping connecting the ports therein with passages in said wings.

7. A core barrel comprising a barrel member, a bit section, said bit section having wings thereon, and means for delivering fluid to the top of said barrel and externally of the interior thereof to and through said wings to the bottom of the hole, said means including a laterally ported plug at the top of the barrel, and piping connecting the ports therein with inclined passages in said wings leading to one end of each wing.

8. A core barrel comprising a single core receiving barrel member and a bit member carrying a core lifter, an intermediate coupling member between said bit member and barrel member, a coupling member in the upper end of said barrel member, and means including passage means in said coupling members and said bit member and a plurality of separate external fluid passage connections along the outside of said barrel member for supplying liquid to the bottom of the hole, each of said connections having a fluid conducting passage therein communicating with a passage in said bit member.

9. A core barrel comprising a core receiving barrel member, a winged bit thereon having fluid conducting passages in its wings, said barrel member forming a connection between the drill rods and said bit, and means including a plurality of separate conduits attached to the outside of said barrel member for delivering fluid externally of said barrel member and through the passages in said wings on said bit to the bottom of the hole.

10. A core barrel having a rod connection closing the upper end thereof, a winged drill bit, and means including a plurality of separate conduits disposed along the exterior of the barrel to deliver fluid from the rods through said connection, externally of said

barrel and through the wings on said bit to the bottom of the hole.

11. A core barrel comprising a single core receiving barrel member, a bit thereon having laterally projecting circumferentially spaced wings formed thereon, said barrel member forming the sole connection between the drill rods and said bit, and means for delivering fluid to the bottom of the hole including passages formed in said wings and a plurality of separate conduits disposed along the exterior of said barrel member.

12. A core barrel comprising a hollow barrel member, a winged bit section, said barrel member forming a connection between the drill rods and said bit section, a winged coupling between said member and said bit section, and means whereby fluid may be delivered externally of said barrel member and through the wings of said bit and coupling to the bottom of the hole.

13. A core barrel comprising an elongated hollow barrel member, a bit section having wings formed thereon, a coupling between said barrel member and said bit section, and means whereby fluid may be delivered from the top of said barrel member and externally of the interior thereof, said means including a laterally ported plug closing the top of said barrel member, passages in said coupling and bit section, and fluid conducting means between said plug and said coupling including a plurality of separate conduits attached to the exterior of said barrel member.

14. A core barrel comprising a single core receiving barrel member, a head therefor, a bit on said barrel member and having a core passage, and means including a plurality of separate longitudinally extending conduits on the exterior of said barrel member for delivering fluid through said head externally of said barrel member and through said bit externally of the core passage therein to the bottom of the hole.

15. A core barrel comprising a plug member, a core receiving barrel member closed at its upper end by said plug member, a winged bit carried on the lower end of said barrel member and having fluid conducting passages in its wings, and means including a plurality of separate longitudinally extending fluid conducting elements on the exterior of said barrel member for delivering fluid through said plug member externally of the barrel member through the passages in said wings on said bit to the bottom of the hole, each of said elements having a fluid conducting passage therein communicating with a passage in said wings.

16. A core barrel comprising a head adapted to be connected to the drill rods, a core receiving barrel member secured to said head, a winged bit on said barrel member

and having fluid conducting passages in its wings, and means including a plurality of separate longitudinally extending fluid conducting elements on the exterior of said barrel member for delivering fluid through said head externally of said barrel member and through the passages in said wings on said bit to the bottom of the hole, each of said elements having a fluid conducting passage therein communicating with a passage in said wings.

17. A core barrel comprising a single core receiving barrel member attachable at its upper end to the drill rods, a winged bit on the lower end of said barrel member and having fluid conducting passages in its wings, and means including a plurality of separate longitudinally extending fluid conducting elements on the exterior of said barrel member for delivering fluid from the rods externally of said barrel member through the passages in said wings on said bit to the bottom of the hole, each of said elements having a fluid conducting passage therein communicating with a passage in said wings.

18. A core barrel comprising a single core receiving barrel member, a head closing the upper end of said member, a winged bit on said barrel member and having passages in its wings, and means for delivering fluid through said head externally of said barrel member and through the passages in said wings on said bit to the bottom of the hole, said means including spaced longitudinally extending passage forming members attached to the exterior of said barrel member and each having a fluid conducting passage therein communicating with a passage in said wings.

19. A core barrel comprising a single core receiving barrel member, a winged bit thereon having fluid conducting passages in its wings, a head on the upper end of said barrel member, and means for delivering fluid through said head and through the passages in said wings on said bit to the bottom of the hole, said means including spaced longitudinally extending passage forming members attached to the exterior of said barrel member and each having a fluid conducting passage therein communicating with a passage in said wings.

20. A core barrel comprising a winged core receiving barrel member, a winged core cutting bit thereon, said barrel member and bit being of substantially the same diameter, and means for delivering fluid externally of the interior of said barrel member through the wings on the latter and said bit to the bottom of the hole.

21. A core barrel comprising a head, a bit, an intermediate operatively connected core receiving barrel member, and means for delivering fluid from said head externally of said

barrel member and through said bit to the bottom of the hole including separate fluid passage forming members attached to the exterior of said barrel member, each of said members having a fluid conducting passage therein.

22. A core barrel comprising a winged head having a fluid inlet therein, a winged bit, and externally closed fluid passages between said head and said bit including a connecting body having separate fluid passage forming members attached to the exterior thereof.

23. A core barrel comprising a head, a bit carrying member and an intermediate operatively connected core receiving barrel member, and separate longitudinally extending fluid passage forming members each having a fluid conducting passage therein and attached to the exterior of said barrel member and to said head and bit carrying member.

24. A core barrel winged substantially throughout its length and comprising a winged core receiving barrel member and a winged bit, the wings on said barrel member being attached to the exterior thereof, and means including fluid conducting passages formed within the wings on said barrel member for delivering fluid externally of the interior of said barrel through the wings thereon to the bottom of the hole, and passage means between said wings for conducting fluid from the hole.

25. In a core drill, a core receiving barrel, a head secured to the upper end of said barrel and having a fluid passage therein, a core cutting bit connected with the barrel at its lower end and having cutters thereon, and a plurality of pipes placed against the sides of said core receiving barrel for conducting fluid from the passages in said head to said cutting bit.

26. In a core drill, a core receiving barrel, a head secured to the upper end of said barrel and having a fluid passage therein, a core cutting bit having cutters thereon, a coupling between said barrel and core cutting bit and having passages therein, and a plurality of pipes placed against the side of said core receiving barrel for conducting fluid from the passage in said head through the passages in said coupling to said cutting bit.

In testimony whereof I affix my signature.
EUGENE WHINNEN.
